UNITED STATES PATENT OFFICE.

JOSEPH SILBERT, OF WINNIPEG, MANITOBA, CANADA.

HALTER.

Application filed January 15, 1925. Serial No. 2,679.

To all whom it may concern:

Be it known that I, JOSEPH SILBERT, subject of the King of England, residing at Winnipeg, in the Province of Manitoba and Dominion of Canada, have invented certain new and useful Improvements in Halters, of which the following is a specification.

This invention relates to improvements in halters and has for one of its objects to 10 provide a device of this character of increased strength and durability without material increase in expense of manufacture.

Another object of the invention is to provide a device of this character with the several members constructed initially of strips of flexible material, preferably raw hide, of double or more widths and folded upon themselves longitudinally with the terminal portions of the longitudinally folded members folded over to form ring receiving loops.

With these and other objects in view the invention consists in certain novel features of construction as hereinafter shown and described and then specifically pointed out in 25 the claims, and in the drawings illustrative of the preferred embodiment of the invention:

Fig. 1 is a perspective view of the improved halter, complete.

Fig. 2 is an enlarged detail of the coupling member between the throat latch and the rear nose strap.

Fig. 3 is a section on the line 3—3 of Fig. 2.

Fig. 4 is an enlarged detail of one of the laced terminals of the members.

Fig. 5 is a section on the line 5—5 of Fig. 4.

Fig. 6 represents a portion of the terminal on the halter members, distended.

Fig. 7 represents one of the lacings detached and extended.

The various members of the improved halter are preferably constructed of raw hide, with each member initially of double width and folded over longitudinally to form two thicknesses of the material and the end portions of the longitudinally folded members folded over to form ring receiving loops and the looped ends secured to the longitudinally folded portions by lacings, also preferably of raw hide.

By this means, the strength and durability of the parts is materially increased with-

out material increase of expense of manufacture or cost of material.

A complete halter is shown in Fig. 1, and includes the nose latch 10, the jaw latch 11, the head strap 12, the cheek straps 13, the throat latch 14, and the coupling strap 15, between the jaw strap 11, and throat strap 14.

Square rings 16 are disposed between the nose strap 12, the jaw strap 11 and the cheek straps 13, while circular rings 17 are disposed between head strap 12 and the cheek straps 13. The lower end of the coupling member 15 is provided with a ring 18 through which folded center of the jaw strap 11 is looped, while a hitching strap 19 is engaged with the loop externally of the ring 18, as shown.

The head strap member 12 is provided with an adjusting buckle 20 as shown. The members 10, 11, 12, 13, and 14 are formed substantially alike and the description of one will suffice for all.

Each of the above members is formed of a strap of flexible material, preferably raw hide, initially of double the width of the completed member, and folded upon itself longitudinally with the end portions folded over upon the longitudinally folded portion to form loops 21 to receive the rings 16 and 17 and the folded over portions secured by lacings as shown.

The arrangement of the lacings whereby the loops of the members 10, 11, 12, 13 and 14, are secured are alike, while the arrangement of the lacing whereby the coupling member 15 is secured, is somewhat different, as hereafter explained.

The manner of applying the lacings to prevent loosening and without fastenings other than the lacings themselves is novel with applicant and arranged as shown.

A portion of one of the halter members, for instance the member 10, is shown distended in Fig. 6 and a portion of one of the lacings at 22 in Fig. 7. Each of the lacings is slightly widened at one end and the widened portion provided with a cleft 23.

The body members 10 to 14 are provided respectively at opposite sides of the fold which forms the loop 21, and indicated by a dotted line in Fig. 6, with five spaced clefts 24 at the outer side of the fold and eight like clefts 24 at the inner side of the fold.

- 2
- The clefts are so located that when the ends of the body members are folded over to form the loops, the five clefts at the outer side of the fold will register with the five clefts next to the inner side of the fold, leaving the remaining three clefts uncovered by the folded over portion, the rings being enclosed in the folded over portion before the lacing is applied.
- 10 The cleft end of the lacing is first wrapped around the folded over portion next to the loop and then passed through the cleft 23 and thence through the adjacent cleft 24 and thence looped around the portion of the lacing at the opposite side of the body member and thence passed in the opposite direction through the second series of registering clefts, and around the superposed portions and thence through the same cleft in the opposite direction and thence looped around the portion of the lacing which has last been looped around the superposed portions and thence laced back and forth through the remaining registering clefts. By this means the plurality of weavings and inter-loopings produces so many turns that the friction is amply sufficient to prevent displacement between the parts, and requires no other fastenings.
- 15 The coupling member 15 is constructed of inner and outer portions, an inner portion initially of double width and double length and folded together longitudinally and likewise folded together intermediate the ends to engage at one fold around the member 14 and at the other fold around the ring 18, the terminals of the inner coupling portion being overlapped and scarfed as indicated at 25 in Fig. 3.
- 20 The outer coupling portion is also of double width and double length and folded together longitudinally and thence folded around the inner coupling member with the terminals overlapping and scarfed as indicated at 26.
- 25 The six thicknesses of material thus produced are pierced by spaced clefts to receive a lacing 27 woven back and forth through the interposed portions as shown in Figs. 2 and 3.
- 30 The halter thus constructed is very strong and durable, inexpensive to manufacture

and can be adapted without material structural change to halters of various sizes and to halters for various species of animals. 55

The preferred embodiment of the invention is disclosed in the drawings and set forth in the specification but it will be understood that modifications within the scope of the claimed invention may be 60 made in the construction without departing from the principle of the invention or sacrificing any of its advantages.

Having thus described the invention what is claimed is:

1. A halter member formed of a section of flexible material initially of double width and folded upon itself longitudinally with the end portions folded upon the same to form loops to receive ring devices, and lacings uniting the folded over terminals to the longitudinally folded member. 70

2. A halter comprising a member formed of a section of flexible material initially of double width and folded upon itself longitudinally with the end portions folded upon the same to form loops to receive ring devices, lacings uniting the folded over terminals to the longitudinally folded member, and an intermediate coupling member formed of a plurality of members of flexible material initially of double width and folded respectively upon themselves longitudinally and the longitudinally folded members inter-folded and formed with loops at the ends 85 to engage the first mentioned folded member by one looped terminal and a ring device at the other looped terminal. 75

3. A halter member formed of a section of flexible material initially of double width and folded upon itself longitudinally with the end portions folded upon the same to form loops to receive ring devices, said folded over end portions and the adjacent portions of the longitudinally folded body 95 being provided respectively with a plurality of clefts which register when the parts are superposed, and a lacing having a cleft at one end and looped through the lacing cleft and back and forth through the spaced registering clefts. 100

In testimony whereof, I affix my signature hereto.

JOSEPH SILBERT.
